WEB SHIFTING MECHANISM

William M. Stocker, Hollis, N. Y., assignor to
Cameron Machine Company, Brooklyn, N. Y.,
a corporation of New York

Application October 20, 1939, Serial No. 300,347

2 Claims. (Cl. 92—71)

The present invention relates to machines in which a web of paper or other flexible material is traveling from one mechanism to another.

A web of paper seldom, if ever, possesses uniform characteristics throughout, but it usually has a variation in thickness in a given zone that persists lengthwise for a long distance and which, when the web is wound into a roll, tends to produce circumferential welts. These welts, if excessive, must be removed, a process that requires rewinding of the paper. The main, though not exclusive, object and feature of this invention is to prevent the formation of these welts during initial winding of the web, i. e. as the web comes from the paper-making machine and as it passes to the winder or reel.

In the accompanying drawings the invention is disclosed in a concrete and preferred form, in which:

Fig. 1 is a somewhat diagrammatic side elevation of a structure embodying the invention;

Fig. 2 is a top plan view of the parts shown in Fig. 1;

Fig. 3 is a detail view looking in the direction of arrow 3 of Fig. 1; and

Fig. 4 is a sectional view substantially on the plane of line 4—4 of Fig. 3.

The paper-making machine is here indicated by a stack of calendering rolls A, and B is the winder, here of the surface-winder type employing two winding drums 1 and 2 that rotate in the same direction to wind the paper into a roll 3 in a well understood manner. 4 is a slitting mechanism which may or may not be employed to slit and/or trim the web, and such slitting mechanism can be either of the shear-cut or score-cut type. The web of paper or other flexible material is indicated at W. C indicates a guiding device that is interposed in the path of the traveling web as it passes from one mechanism or machine to the other.

Guiding device C constitutes a means to effect periodic bodily reciprocation of said web in a direction at right angles to its direction of travel to thereby tend to prevent the formation of a persistent thick zone into a circumferential welt. The guiding device consists essentially of a freely rotatable roller 5 mounted to bodily reciprocate lengthwise of its axis in bearings 6 and 7. Roller 5 is driven by web W, the latter being trained around said roller by means of two rollers 8 and 9. Suitable means are provided to convert the rotating movement of roller 5 into a bodily movement of reciprocation of said roller. In the present instance, roller 5 is provided with a worm 55 10 at one end that engages a worm wheel 11 ro-

tatably mounted in a slide 12 secured to the shank of roller 5 and slidably carried by stud 13 of bearing 6. Mounted on bearing 6 are two bearing brackets 14 that support a pivot 15. 15 5 are links that connect said pivot with cranks 17 that rotate with worm wheel 11. It will now be understood that rotation of roller 5 causes rotation of worm wheel 11 and therefore of cranks 17, and that rotation of the latter, by reason of links 16, anchored on pivot 15 of stationary bearing brackets 14, causes periodic bodily reciprocation of slide 12, worm wheel 11, worm 10 and roller 5.

It will thus be seen that the periodic bodily reciprocation of roller 5 is due to its own rotation, and that the speed of said bodily reciprocation depends upon the speed of the web and is not dependent upon outside factors and, furthermore, by subjecting the web to the reciprocating bodily movement before it is wound, the tendency to form circumferential welts, that might later require removal, is minimized if not completely prevented.

I claim:

1. In a machine in which a web of paper is traveling from one mechanism to a winder, means to effect periodic bodily reciprocation of said web in a direction at right angles to its direction of travel and in proportion to its speed of travel including: a freely rotatable roller mounted to bodily reciprocate lengthwise of its axis, around which roller the web is trained and by which it is rotated, means to train said web around said roller to thereby rotate the latter by frictional engagement and to cause said web to follow endwise reciprocation of the roller, and means, actuated by said roller upon rotation thereof, to effect lengthwise bodily reciprocation of said roller.

2. In a machine in which a web of paper is traveling from one mechanism to a winder, a group of three rollers interposed in the path of travel of the web, one of said rollers being intermediate the other two and being mounted to rotate freely and to bodily reciprocate lengthwise of its axis, and the other two rollers serving to train the web around the intermediate roller to thereby rotate the latter by frictional engagement with the traveling web and to cause said web to follow endwise reciprocation of the intermediate roller, and means, actuated by the intermediate roller upon rotation thereof, to effect lengthwise bodily reciprocation of said intermediate roller in proportion to the speed of travel of the web.

WILLIAM M. STOCKER.
